UNITED STATES PATENT OFFICE.

JOHN S. GOLDSMITH, OF NEW YORK, N. Y.

CHECK-TICKET FOR MESSENGER SERVICE.

SPECIFICATION forming part of Letters Patent No. 337,762, dated March 9, 1886.

Application filed June 9, 1885. Serial No. 168,169. (Specimens.)

To all whom it may concern:

Be it known that I, JOHN S. GOLDSMITH, a citizen of the United States, residing at New York, in the State of New York, have invented 5 a new and useful Improvement in Check-Tickets for Messenger Service, of which the following is a specification.

The primary object of this invention is to prevent or repress certain fraudulent practices 10 on the part of dishonest messengers and clerks in the employ of district-telegraph companies and like messenger agencies.

Another object is to adapt one series of tickets for economical use in all the several varieties of service usually provided for. 15

This invention consists, first, in an improved messenger-ticket provided with permanent and conspicuous time-control characters in distinctive style, representing a short-time 20 period, as indicated by ordinary time-pieces, to which its issue for use is limited, for controlling entries in the customary blank under "Called," and thereby preventing fraud; secondly, in a series of messenger-tickets having 25 on the face of each suitable printed matter and blanks common to all, and provided, serially, with such time-control characters representing successive uniform short-time periods, those for each time period being printed on more or less 30 numerous tickets, the whole series being also consecutively numbered to prevent substituting, destroying, or suppressing tickets without detection; and, thirdly, in a messenger-ticket having, in addition to ordinary printed 35 matter and blanks, an extra blank to receive the entry "Paid" or "Charge," or a symbol representing the same, together with time-control characters and a serial number, as aforesaid, and provided, further, with a paster, 40 of distinctive color, the latter indicating the proper entry in said extra blank, and having on its face printed matter appropriate to calls from a particular call-box, whereby one series of tickets is adapted to take the place of four 45 kinds of tickets heretofore used, as hereinafter more fully set forth and claimed.

A sheet of drawings accompanies this specification as part thereof.

Figure 1 of the drawings is a face view of a 50 messenger-ticket, illustrating the first part of this invention. Figs. 2 and 3 are face views of illustrative "pasters;" and Fig. 4 is a face

view of another ticket of the series to which the former belongs, provided with one of said pasters, and with its blanks filled. 55

Like letters of reference indicate corresponding parts in the several figures.

In carrying out this invention I print tickets $T T^2$, of suitable paper, with appropriate ordinary permanent matter, to which I super-add, in distinctive style, conspicuous time-control characters $a b$, indicating on each ticket a period of time to which its issue for use is limited, and, furthermore, preferably, consecutively number all the tickets of each 60 series, as represented at $c d$. Said ordinary permanent matter in the examples consists of the words "Manhattan District Telegraph Co. Date ..... Messenger ..... Called ..... Returned ..... Occupied ..... 70 Expenses ..... Where sent ..... Received by ..... Please sign your name," with the lines which separate and supplement the same.

In addition to the blanks indicated by space- 75 marks in the foregoing quotation, a row, e , of blanks is provided under said headings, "Messenger," "Called," "Returned," "Occupied," and "Expenses," and an extra heading blank, f , in line with said headings to receive the word "Paid," or the word "Charge," or symbols representing the same, respectively, according to whether the ticket is used 80 as a cash-ticket or a charge-ticket.

To furthermore adapt one and the same 85 series of tickets for use as cash-tickets and charge-tickets, I combine therewith two series of pasters, $P Q$, of different contrasting colors—red and yellow, for example—indicating, respectively, cash and charge, provided 90 with call-numbers g , district-numbers h , folio-numbers i , and the corresponding names and addresses of lessors of call-boxes with whom accounts are kept, including on cash-ticket pasters P the names, &c., of hotels, banks, 95 and the like, furnished with public call-boxes. The backs k of these pasters are provided with adhesive gum, so that by simply dampening them on a wet sponge they are prepared for application to the tickets. On receiving a 100 call the appropriate paster is applied to a ticket, as represented in Fig. 4, and the latter is then ready for use.

Heretofore cash and charge have been in-

dicated by color; but tickets of each color were provided with the ordinary permanent matter appropriate thereto respectively, and some of each of these were printed with the 5 additional matter carried by my pasters P Q, while others of each color were used blank, thus making four kinds of tickets kept in each district office. The pasters are relatively inexpensive and small, while the single series 10 of tickets proper so provided for materially facilitates the practical application of my said time-control characters *a b* and consecutive numbers *c d*, and simplifies the ticket system.

In using ordinary messenger-tickets frauds 15 have heretofore been successfully practiced and concealed in ways examples of which I will now set forth, referring for illustration to the tickets T T', which for this purpose must be supposed to be without said characters *a b* 20 and numbers *c d*.

A has an account with the company and uses charge-tickets. He calls a messenger at nine o'clock, and dismisses him so that he should return to the district office at five minutes past ten, having authorized an expenditure of twenty cents for car-fare. The time occupied is one hour and five minutes, and charged at thirty cents per hour, plus expenses, the charge against him is fifty-three 30 cents. Now, the clerk makes no entry under "Called" until the messenger's return. Then if no detective has been in he enters "Called, 9.20; returned, 10.05; occupied, 45; expenses, 30; charge, 53," and pockets ten cents, trusting to the identity of the amount charged with the correct amount to hide the fraud on the company; or he may enter an earlier hour under "Called," and charge for time not occupied by the customer, thus defrauding the 40 latter in order to bring up the apparent gross earnings of the office, so as to cover other pilfering; or the messenger, for the same purpose or purposeless, may loiter on his way, and thus defraud the customer of both time 45 and money.

B is a transient patron using a public call-box. The messenger who responds carries, consequently, a cash-ticket, T' P, Fig. 4. He is called at 9.20, for example, and returned at 50 eleven o'clock, having been occupied one hour and forty minutes, for which B is charged by the messenger fifty cents, as noted in Fig. 4. The messenger is, instead, entered by the clerk as called at ten o'clock, for example, and twenty 55 cents, falsely entered under expenses, is pocketed or divided with the messenger, the latter being generally in collusion with the clerk.

Pilfering is accomplished and hidden in numerous other ways by false entries under 60 "Returned" and "Occupied." These can be effectively guarded against in other ways, provided correct entries under "Called" can be insured. They will not be particularly set forth herein, as guards against them form no 65 part of the present invention.

Correct entries under "Called" are insured by means of said time-control characters *a b* on

the tickets. The characters shown "9 to 9.15" and "9.15 to 9.30," represent successive periods of fifteen minutes each. The full series 70 begins with "12 to 12.15" and ends with "11.45 to 12," corresponding with the quarter-hour divisions of ordinary twelve-hour time-pieces. Longer or shorter periods could be adopted; but they would in all cases be uniform, and 75 fifteen minutes is believed to be the best limit for the use in question. A sufficient number of tickets would bear each imprint—"9 to 9.15," for example—to meet the estimated maximum demand or capacity of the office during 80 the period, and the respective sets would be replenished each day, for example. Said ordinary permanent matter being printed in black, the characters *a b* would preferably be printed with ink of red or some other contrasting color, and two colors—red and green, for example—may distinguish the hours before noon from those after noon, or "day" hours from "night" hours in a double series; but such complications are deemed unnecessary and undesirable. Owing to the addition of said characters *a b* the messenger and the caller are both notified immediately of the beginning of the time to be charged for. Said characters themselves indicate the time within a quarter 95 of an hour at most, and call attention to the entry under "Called," which is the entry they control, as aforesaid; consequently there can be no overcharge nor undercharge at this end of the service of the messenger, and with the 100 reception of the tickets controlled in any approved way there can be no hiding of pilfering in the manner aforesaid, and loitering on the part of the messenger will be prevented or detected, thus insuring prompt service and 105 correct returns. The above depends, of course, to some extent on inability on the part of the clerk to substitute one ticket for another, or 110 destroy or suppress tickets, without detection. This can be guarded against by simply counting the tickets and charging the clerk with a given number; but it is accomplished more effectively by said consecutive numbers *c d*, a 115 number appearing on each ticket different from those of every other ticket in the series, so that the clerk can be held strictly accountable for each ticket issued to him, and the exact time at which a missing ticket was issued 120 can be ascertained by ascertaining the time-control characters thereon, so as to aid in investigating its loss. These numbers are printed on the tickets by ordinary numbering-machines, all the tickets of every kind in the series originally and those added from time to 125 time being consecutively numbered.

My improved check-tickets are primarily designed for use in connection with my "Apparatus for Controlling the Issue of Time-Checks," and "Apparatus for Receiving Time-Checks," and as part of my "Time-Check System," which are described and claimed under these titles in previous specifications forming part of applications for Letters Patent of the United States filed and serially numbered as 130

follows, viz: December 8, 1884, No. 149,798; December 8, 1884, No. 149,799, and March 21, 1885, No. 159,650.

Said apparatuses and system form no part of the present invention; but reference is made to said specifications thereof for means for preventing the issue of other than the correct ticket at each call and means for insuring correct entries under "Returned" and "Occupied," as aforesaid.

Having thus described my said improvement in check-tickets for messenger service, I claim as my invention and desire to patent under this specification:

15 1. A messenger-ticket having on its face suitable ordinary printed matter, including the heading "Called," and blanks for entries thereon, including a blank under said heading in which to express the beginning of the period 20 of service to be charged for, and provided with permanent and conspicuous time-control characters, as "9 to 9.15," in distinctive style, representing a short-time period, as indicated by ordinary time-pieces, to which its issue for 25 use is limited, for controlling entries in said blank under "Called," and thereby preventing fraud, substantially as herein specified.

2. A series of messenger-tickets having on the face of each suitable printed matter and 30 blanks common to all, and provided serially

in distinctive style with permanent and conspicuous time-control characters, as "9 to 9.15," "9.15 to 9.30," and so on, representing successive uniform short-time periods to which the issue of the respective tickets is limited, the 35 time-control characters for each time period being printed on more or less numerous tickets, the whole series being also consecutively numbered, substantially as herein specified, for the purposes set forth.

3. A messenger-ticket having on its face suitable or ordinary printed matter, and blanks for entries thereon, together with an extra heading-blank, *f*, to receive the entry "Paid" or "Charge," or a symbol representing the same, 45 and provided with permanent and conspicuous time-control characters in distinctive style, consecutive numbers, and a poster of distinctive color, the latter indicating the proper entry in said blank *f* and having on its face 50 printed matter appropriate to calls from a particular call-box, substantially as herein specified.

Dated at Brooklyn this 4th day of June, 1885.
